UNITED STATES PATENT OFFICE.

JOSEPH J. GEST, OF CINCINNATI, OHIO.

DESIGN FOR A SOAP BAR.

SPECIFICATION forming part of Design No. 12,106, dated January 4, 1881.

Application filed December 15, 1880. Term of patent 7 years.

To all whom it may concern:

Be it known that I, JOSEPH J. GEST, a citizen of the United States, residing at Cincinnati, Hamilton county, Ohio, have invented and produced a new and original Design for Soap Bars, of which the following is a specification, reference being had to the accompanying drawings, forming part thereof.

The leading feature of my design consists in the formation in opposite sides of a bar of soap of similar long and deep trenches or indentations, which so nearly meet at the mid-thickness of the bar, and which extend so near the edges of the same as to present the appearance of being separated into a series of equal subdivisions, thus presenting a pleasing variety of configuration. Associated with this feature is a panel on each face of each subdivision at a different elevation to the marginal or surrounding surface.

In the accompanying drawings, Figure 1 is a partially-sectional elevation of a bar of soap embodying my design. Fig. 2 is a face view of the said bar.

Each subdivision is nearly separated from those next to it, both laterally and longitudinally, by deep and narrow trenches A A', which nearly meet each other in the substance of the bar, and which extend almost to the edges of the bar. Quadrangular orifices B, which extend entirely through the bar, are provided at the intersections of the planes of separation. Each subdivision has on each face a panel, C, at somewhat different elevation to the surrounding margin D.

I do not claim marking off a bar of soap into equal divisions, paneled or otherwise, such bars being old and well known; but

I claim—

The design for a bar of soap, as herein described and shown.

In testimony of which invention I hereunto set my hand.

JOSEPH J. GEST.
